CLAIM

The ornamental design for an element for jewelry as shown and described.

DESCRIPTION

FIG. 1 is a front, right-side, top perspective view of an element for jewelry, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines depict portions of the element for jewelry that form no part of the claimed design.

1 Claim, 2 Drawing Sheets
